UNITED STATES PATENT OFFICE.

JOHN H. LINDSAY, OF BROOKLYN, NEW YORK.

GAS VALVE.

Application filed April 16, 1925. Serial No. 23,623.

To all whom it may concern:

Be it known that I, JOHN H. LINDSAY, a citizen of the United States, and a resident of the city of New York, borough of Brooklyn, in the county of Kings and State of New York, have invented a new and Improved Gas Valve, of which the following is a full, clear, and exact description.

This invention relates to gas valves and 10 more particularly to a gas valve which will close automatically when the temperature reaches a point sufficient to destroy or melt a fusible connection, and which also can be released manually to shut off the supply of 15 gas to a meter and to the building.

Escaping gas in the event of fire is not only a source of great danger to the occupants of the building and to the firemen but greatly increases conflagration and 20 renders the saving of property and lives extremely hazardous. It is the purpose of my improved valve construction to provide means which may be manually operated by the firemen or by any one to shut off the 25 supply of gas to the building, and, furthermore, will operate automatically when the temperature reaches a point sufficient to destroy or break down fusible links which form a portion of the valve controlling 30 means.

With this and other objects in view, the invention consists in certain novel features of construction and combinations of parts, which will be more fully hereinafter described and pointed out in the claims.

In the accompanying drawings—

Figure 1 is a view partly in section and partly in elevation, and more or less diagrammatically illustrating how my improved valve is employed in connection with a building;

Figure 2 is a view in side elevation of my improved valve;

Figure 3 is a view, partly in elevation and partly broken away, illustrating the fusible link construction;

Figure 4 is a view in longitudinal section through the valve;

Figure 5 is a view in longitudinal section 50 on the line 5—5 of Figure 4.

1 represents the casing of my improved valve, which may be located in vertical position as shown, or in horizontal or other position in accordance with the desire of the user and the convenience of assemblage, and while I shall describe the valve as in a

vertical position, it is obvious the invention is not limited to the position of the valve.

The casing 1 is provided with an inlet 2 at its lower end for the reception of a supply pipe 3 screwed therein, and said casing is provided in at least two sides with outlets 4 and 5. One of these outlets is closed by a plug 6, which latter has a wrench-receiving portion 7 thereon, the latter adapted to be 60 cut off after the plug is screwed into its closed position so as to prevent tampering with the valve.

One of the outlets, for example the outlet 4, is connected by a pipe 8 with the gas 70 meter 9, and this pipe 8 has a manually movable valve 10 therein, as is customary in the art. The valve as a whole may be located in a suitable box 11 in the cellar or other 75 part of the building indicated by the reference numeral 12.

The valve is manually operated by a flexible device, which we will assume for purposes of description as a cable 13 which is located in a tubular housing 14 and terminates in a box 15 on the outside of the building so that the firemen may have ready access to the end of the cable to manually release the valve, as will more fully herein-after appear.

The top of valve 1 is closed by a screw-threaded plug 16 having a wrench-receiving enlargement 17 thereon. Inside the valve casing 1 a circular tapering valve seat 18 is provided which is located in the inlet passage of the valve chamber and is adapted to be closed by a valve 19. This valve 19 has a stem 20 and constitutes a stem projecting from both sides of the valve.

An arm 21 is cast integral with the inlet portion of the valve casing and has a ring 22 thereon constituting a guide for one end of the valve stem 20. The other end of the valve stem 20 is guided in a tubular barrel 23 integral with the plug 16. A coil spring 24 is located around the stem 20, around the barrel 23, and bears at one end against the plug 16. At the other end the spring bears against the valve and tends to close the valve with the necessary pressure against the pressure of the gas flowing through the valve chamber.

A shaft 25 is mounted in suitable bearings 26 in the sides of the valve casing adjacent its upper end and this shaft is located in a position appreciably to one side of the valve stem, as shown clearly in Figure 4. A pair

of crank arms 27 is secured to the shaft 25, preferably by set screws 28, and these arms 27 are pivotally connected at their free ends by links 29 with a cross pin 30 projected 5 through the hub 31' of valve 19 and also through the stem.

The stem portions at opposite sides of the valve have perfect alignment and are maintained in perfect alignment by the bearings, 10 one bearing constituting the sleeve 23 and the other the ring 22.

On an integral stub 40 projecting from casing 1 I provide a hub 41, and preferably provide on said hub a pair of integral crank 15 arms 31 and 32 at an angle to each other. It is to be understood that only one of these arms is actually in use, the other being provided merely in order that it may function in the event that the valve is positioned horizontally. 20

A pair of fusible links 33 is secured to the hub 41, preferably by a set screw 34', and these links constitute parallel crank arms which at their free ends provide rotary 25 mounting for a cylindrical roller 34, the latter being used to reduce friction to a minimum.

On the outer end of the shaft 25, a crank arm 35 is secured, and this crank arm 35 at 30 its free end has a semicylindrical enlargement 36 which is adapted to engage the roller 34 and held thereby in a set position. When the arm 35 is swung in a direction to open the valve, as shown in Figures 4 and 35 5, the links 33 can be moved so as to receive the end of the arm 35 against the roller 34 and hold the valve in open position with the spring 24 under the desired tension. When a pull is had on the cable 13 the free ends of 40 the links 33 will be moved downwardly to release the crank arm 35, and the spring 24 will close the valve.

If the temperature rises to a point sufficient to melt the fusible links 33 the arm 35 45 will be released and the spring can close the valve. Hence, my improved valve may be operated either manually or automatically, as the case may be.

In opening the valve the arm 35 is swung 50 to the right of Figure 2 and causes the shaft 25 to turn, the crank arms 27 exerting a pull on the links 29 to open the valve.

As these links 29 are pivotally connected at both ends they assume any necessary position without exerting lateral thrust on the valve stem, and hence friction is reduced to a minimum.

My improved valve has many advantages, 60 some of which may be enumerated as follows:

The valve is maintained at all times in proper alignment with its seat, the fusible links being in multiple to render the device strong and positive.

65 The operating means for opening the

valve is strong and positive and reduces friction to a minimum.

The mechanism is such that the valve stem will stay in alignment at all times.

The movement controlling the valve stem 70 is positive and friction is reduced to a minimum.

The moving of the valve stem by the pivoted links, which assume any necessary positions, prevents lateral thrust and friction on 75 the stem and valve.

The construction of the valve and the valve casing prevents any water lodging in the valve body.

The design of valve allows a full area of 80 pipe connection.

The construction of fusible links allows of rapid and easy renewals.

The construction of the valve is so arranged 85 as not to interfere with pipe connections.

The outlets are so arranged that the valve can be set in a vertical, horizontal or any other position desired.

The controlling links are so arranged that 90 the valve can be operated by a manual pull on a cable either in vertical or horizontal position.

The valve is so arranged that any part of 95 the interior can be easily removed without removing the valve from the line.

The valve is so constructed that it can be cleaned.

Guides on the valve stem keep the spring 100 in positive position.

The double links will conform to any position and keep the valve in alignment.

The valve will positively close when the fusible links melt or when the cable is pulled.

Friction in so far as is possible is eliminated.

The valve cannot be tampered with when once installed.

The interior of the valve is larger in area 110 than the outlets.

There is no cushion to resist the movement of the valve.

While I have described my invention as a gas valve, it is obvious that the same general construction of valve can be utilized in connection with air, steam and water as well as gas.

Various slight changes and alterations 115 might be made in the general form of the parts described without departing from my invention, and hence I do not limit myself to the precise details set forth but consider myself at liberty to make such slight changes and alterations as fairly fall within the spirit and scope of the appended claims.

I claim:

1. A valve of the character described, comprising a casing having an inlet and an outlet located in the casing at right angles to each other, a valve adapted to close the inlet, 120

130

means guiding the movement of the valve in a straight line, a spring adapted to close the valve, a shaft projecting into the casing, a pair of narrow crank arms on the shaft, 5 links connecting the ends of the crank arms with the valve, a crank arm on the shaft outside of the casing, and a movable member adapted to engage said last mentioned arm and hold the valve in open position, said 10 member adapted to be manually moved to release the arm and permit the closing of the valve.

2. A valve of the character described, comprising a casing having an inlet at one end 15 and an outlet in the side thereof and having an opening at the end opposite the inlet, said casing having a valve seat adjacent the inlet, a plug removably closing the end of the valve casing opposite the inlet, a tubular 20 barrel on the plug projecting centrally into the casing, a valve adapted to engage the seat, a stem fixed to the valve and located at both sides of the valve, one end of said stem movable in the barrel, a fixed ring guide located centrally in the inlet portion of the casing and receiving the other end of the stem, a spring between the valve and the plug normally exerting pressure to close the 25 valve, a shaft projecting through the casing, a pair of crank arms on the shaft having their free ends at opposite sides of the spring, links connecting the crank arms with the valve, and means outside of the valve for turning the shaft to open the valve.

20 3. A valve of the character described, comprising a casing having an inlet at one end 25 and an outlet in the side thereof and having an opening at the end opposite the inlet, said 30 35

casing having a valve seat adjacent the inlet, a plug removably closing the end of the valve casing opposite the inlet, a tubular 40 barrel on the plug projecting centrally into the casing, a valve adapted to engage the seat, a stem fixed to the valve and located at both sides of the valve, one end of said stem movable in the barrel, a fixed ring guide located centrally in the inlet portion of the casing and receiving the other end of the stem, a spring between the valve and the plug normally exerting pressure to close the 45 valve, a shaft projecting through the casing, a pair of crank arms on the shaft having their free ends at opposite sides of the spring, links connecting the crank arms with the valve, and means outside of the valve for turning the shaft to open the valve.

50 4. A valve of the character described, comprising a casing, a spring-pressed valve in the casing, a shaft projecting through the casing, means on the shaft operatively engaging the valve, an arm on the shaft outside of the casing and adapted to be moved to a position to open the valve against action of the spring, a hub mounted on the casing, a crank arm fixed to the hub and adapted to be manually moved, a pair of fusible links 55 also fixed to the hub, and a roller carried by the fusible links and adapted to be engaged by the free end of the arm outside of the casing whereby the valve is held in open position and released so as to automatically 60 65 70 close when the hub is turned manually or when the fusible links are destroyed.

JOHN H. LINDSAY.
